The ornamental design for a mirror, picture and hanger device for a locker, as shown and described.

DESCRIPTION

FIG. 1 is a front perspective view of the mirror, picture and hanger device for a locker, in accordance with my invention; FIG. 2 is a front elevational view thereof;

FIG. 3 is a top plan view thereof;

FIG. 4 is a bottom plan view thereof;

FIG. 5 is a right side elevational view (the left side view is a mirror image thereof); and,

FIG. 6 is a rear elevational view thereof.

The rear view shown in FIG. 6 and the dashed lines in FIGS. 1 and 2 are not claimed as part of the invention.
